UNITED STATES PATENT OFFICE.

CHARLES BIGEON, OF CINCINNATI, OHIO.

BED-BOTTOM.

SPECIFICATION forming part of Letters Patent No. 326,096, dated September 15, 1885.

Application filed December 12, 1884. (No model.)

To all whom it may concern:

Be it known that I, CHARLES BIGEON, a citizen of the United States, residing at Cincinnati, Ohio, have invented new and useful Improvements in Bed-Bottoms, of which the following is a specification.

My invention relates to spring bed-bottoms of the class wherein an elastic web is formed on or attached to a frame. It consists, first, in the improved construction of the elastic web, the same being made up of a number of flat detachable wire springs bent in curved form, with projecting ends suitable for attaching to the curved loops of two adjacent springs, a connected series of which thus forms a continuous surface, and, secondly, in the provision and arrangement of flexible supporting braces mounted on the lower frame-work, and extending diagonally upward to points on the outer railing or frame, upon and between the sides of which is stretched the elastic web, all as more fully hereinafter pointed out.

Mechanism illustrating my improvement is shown in the accompanying drawings, in which—

Figure 1 is a perspective view of a bed-frame with braces and side railing, the web removed; Fig. 2, a plan of a portion of web and side and end rail; Fig. 3, a detail view of the curved spring; Fig. 4, a detail view illustrating one method of attaching the flexible braces on the lower frame, and Fig. 5 a form of flexible brace and its attachment.

In the drawings, A designates the end parts of the lower frame, B the side pieces, and A' the cross-piece, one or more of which may be used.

a designates the flexible braces attached to the rails R above, and extending diagonally to suitable points on the side pieces, B, or the cross-piece A'. I may omit the latter and attach the end braces directly on the sides B at front and back in the drawings.

I form the curved springs S of wire of suitable gage, and bend, preferably, to the form shown, providing the projecting ends h h with suitable engaging-hooks for attaching to adjacent springs; and with these curved springs or loops I build up an elastic web, W, in which the projecting ends of each loop are hooked to the curved part of a loop at either side. Each loop receives through its crossed

ends a closing pull resisted by the elasticity of the curve, and transmits the strain to the adjacent hook ends of other loops, the whole forming a strong and elastic surface.

In forming the web I may interpose at convenient intervals lines of plain rings r, for convenience in detaching the web in strips for ready package, and I preferably attach the hook ends h h to rings upon the end and side rails for a similar purpose.

I provide the foot of the braces a with coiled springs on central supporting-cores fastened to the frame, the tendency of which to uncoil throws the free ends of the braces toward the vertical and resists depression toward the horizontal positions; or I may form the braces themselves of flexible material sufficiently stiff to resist the thrust when the bed is occupied, and bent in a curve upward, in which case the same are secured at the foot, and bending takes place in the length of the brace about its fixed end as a center. These braces are loosely clasped upon the bounding rails R, and chains or cords c are provided, attached to the rails and the lower frame, preventing distortion of the web-surface from possible inequalities in the strength of the spring at the foot of each brace or the spring of the brace itself.

Thus constructed, the bed-bottom operates as follows: The elastic web or mat, being stretched between the side and end rails, forms a flat surface, which, upon receiving a weight, yields or stretches, due to the closing up of the curved loops. As the web stretches it is allowed to sink, compressing or winding up the springs at the foot of the diagonal braces, or bending the braces toward a straight line in case the braces in Fig. 5 are used, since it carries their free ends downward, and the distribution of strain is thus made in the most perfect and natural manner.

The advantages of this invention may be enumerated as, first, superior elasticity of surface; second, strength and elasticity in the vertical direction; third, accessibility for cleaning and removing insects and the prevention of the same; fourth, evenness of surface, the ease with which all the springs may be removed or replaced when required for dismounting or setting up a bed, all of which features are here met with in a marked degree.

I am aware that a wire fabric for bed-bottoms has been heretofore used, consisting of wire loops hooked together; but such loops were of different forms, and not, therefore, 5 interchangeable as between themselves; and, moreover, although embracing loops approximately similar in form to mine, the same were hung together in such manner as to involve a tensional strain instead of a compressional 10 strain, as in my improvement; nor is such fabric equally elastic in both directions, as in my improvement.

I am also aware that a frame composed of 15 separate end and side pieces has been used in spring bed-bottoms; but in such case the opposite rails were held by ties crossing each other and secured together, and the whole supported upon spiral springs acting vertically. Such 20 construction, as is obvious, could not be used with a fabric elastic in both directions.

I claim and desire to secure by Letters Patent of the United States—

1. The elastic mat for bed-bottoms, composed of the detachable and interchangeable 25 wire loops S, formed and hung together as shown, the free arms of one connecting with the circles of adjacent loops, and joined along one or more medial lines and to the containing frames with plain rings or links, substantially as set forth.

2. In a spring bed-bottom, the combination 30 of a permanent base-frame, an upper frame for the wire fabric, consisting of separate and independently-movable end and side rails, and 35 spring-braces secured at one end to the rail of the upper frame and passing diagonally be-

neath and across the fabric to the lower frame, so that the depression of the upper frame tends to thrust the corresponding upper rails apart, substantially as set forth. 40

3. The combination, in a spring bed-bottom, 45 of a wire fabric elastic in both directions, a supporting-frame consisting of separate side and end pieces, a permanent base-frame, and spring-braces supporting the end and side pieces of the mat-frame from opposite or intermediate braces of the base frame, substantially as set forth.

4. A spring bed-bottom composed of a lower frame, A A B B, supporting the foot of the 50 braces a, the flexible braces a extending thence diagonally upward and clasped to the rails R above, the rails R, and the elastic fabric W, stretched between the rails R, all constructed and arranged substantially as set forth. 55

5. An elastic mat for bed-bottoms, composed of integral and interchangeable wire loops, each consisting of a wire of given length bent to circular form, with crossed projecting ends, and hung together with the projecting ends 60 hooked into the circles of adjacent loops, forming a fabric elastic in both directions, and in which the strains upon the loops are compressional, substantially as set forth.

In testimony whereof I have hereunto set 65 my hand in the presence of two subscribing witnesses.

CHARLES BIGEON.
